UNITED STATES PATENT OFFICE

HAROLD F. SCRIBNER, OF NEW YORK, N. Y.

LOCATING DEVICE FOR PLIER PUNCHES

Application filed July 12, 1928. Serial No. 292,272.

This invention relates to an improvement in locating devices for punches and more particularly to hand punches of the plier type adapted to perforate paper, cardboard, straw and other similar materials.

The device is particularly adapted for office use since it is the practice in the orderly and systematized filing of papers in a business office to keep all the correspondence, etc., relating to a particular item in a separate file and in their chronological order; thus it becomes necessary to fasten the documents together with a semi-permanent fastener in order that the sheets do not become lost or out of place. The difficulty, however, has been in the punching of the individual sheets in the same predetermined position to receive a suitable fastener so that when attached to the main file, all the papers will be evenly and orderly arranged.

As used in this connection one of the primary objects of this improvement is to provide a means for facilitating the accurate positioning of the punch elements with respect to the sheet to be perforated so that two or more of the perforated sheets may be clipped together with a suitable fastener in perfect alignment.

Heretofore it has been impossible to so locate a punch of the plier type with respect to the corners of successive sheets and secure any degree of uniformity in the location of the perforations. The result has been that the various papers of a given group projected at their edges and thus rendered susceptible to easy and serious damage.

Heretofore uniformity in the location of the perforations from one edge only of a sheet has been attained by providing a punch with a substantial base portion and mounting thereon numerous and complicated guiding devices. However, the time consumed in using a punching machine of this type has been found prohibitive and entirely unsuitable for a filing clerk in that the machine necessarily must occupy a fixed position in the office and the clerk is obliged to bring the papers to the machine and then take them to the files.

To overcome this disadvantage of the prior

devices this invention has for an object to provide a punch of the plier type with a simple, accurate and dependable paper locating device adapted to be secured to the punch and thus rendered always accessible to the user.

Another object of my invention is to provide a perforating tool with a device for locating two adjacent edges of sheets of paper or similar material in a predetermined position with respect to the perforating elements whereby the perforated articles when fastened together with a common fastener will have their adjacent edges uniformly aligned.

Another and further object of my invention is to equip a hand punch of the plier type with a simple and accurate locating device whereby the time spent in locating the punch in a predetermined position with respect to the article to be punched is reduced to a minimum and thus the punching of a number of articles is greatly expedited.

The improved locating device comprises essentially an ordinary hand punch and a flat sheet of metal having upturned edges disposed at an angle of 90° and adapted to be soldered or otherwise secured to one of the jaws of the punch in such a position that the knife carried by the other jaw will engage its correspondingly contoured opening in the plate carrying jaw midway, or 45°, from either of the upturned edges of the metal plate.

The user in operating the punch inserts the article to be perforated between the jaws until its edges contact with the abutments formed by the upturned edges of the metal plate and proceeds to operate the punch in the usual manner. Thus it will be seen that without the aid of complicated edge guides, or other easily disarranged mechanisms, a simple and highly accurate locating device is provided that insures the punching of successive sheets of paper, etc., in the same predetermined position.

Other objects and advantages will be in part indicated in the following description and in part rendered apparent therefrom in connection with the annexed drawings.

To enable others skilled in the art so fully

to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:

Figure 1 is an elevational view of an ordinary hand punch depicting this invention. Fig. 2 is a plan view of the locating device. Figs. 3 and 4 are front and side views respectively thereof. Fig. 5 illustrates a method of detachably securing the plate to the punch.

Referring more particularly to Fig. 1 the tool consists essentially of a pair of pivotally connected handles 10 having jaws 11 and 12 pivotally secure thereto. Near the outer end of the jaw 11 is mounted a knife or male member 13 of the punch. The member 13, as will be understood, may be of any shape or contour desired since the particular shape of the blade in no way affects the utility of the device. The lower jaw 12 is provided near its outer end with a complementary socket 14 corresponding in contour with the blade 13, the two parts operating as die members to the end that when brought into operative relation they serve to remove a portion of an interposed sheet of paper corresponding in contour therewith.

Between the jaws 11 and 12 is a stripper member 15, preferably carried by the latter, which serves to disengage the knife or punching element 13 from the article punched thereby facilitating its removability. The lower jaw member 12 carries also a locating plate 16 having an opening 17 similar to or larger than the aperture 14 to permit the knife 13 to pass therethrough and be engaged by the opening in the jaw 12 and thus complete a punching operation.

It has been found desirable in the filing of papers to punch the sheets and fasten them together with a suitable fastener and in order to create a neat appearance and to preserve the paper in the various files as long as possible it is necessary to accurately locate the punch in a predetermined position on the papers so that when punched and fastened together their edges will be aligned.

To this end, I have formed the locating plate 16 with upturned edges 18 and 19 and secured it preferably to the lower jaw of the punching tool whereby the sheet may be inserted until its edges strike the abutments 18 and 19 formed by the upturned edges of the plate, and in this manner each sheet may be perforated the required distance from its edges and uniformity in the punched sheets is attained.

The upturned edges of the plate 16 are disposed at substantially an angle of 90° from each other, diverging outwardly from a point

between the die elements and the pintle of the handles 10. The forward edge of the plate is unobstructed and serves as a guide surface which more readily permits the article to be inserted between the punch elements. A practical and inexpensive method of securely attaching the locating plate to an ordinary punching tool of this type is by punching from the base of the plate 16, short tabs 20 and 21 adapted to be folded under the jaw 12 and soldered at the point where their ends come together or over-lap.

Fig. 5 illustrates an alternative method of removably attaching the locating plate to the jaw of the punch as by means of a set screw 22. However, any other suitable means may be employed for securing the plate to the tool or the locating device may be formed integral therewith if desired.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

Having thus revealed this invention, I claim as new and desire to secure the following combinations and elements, or equivalents thereof, by Letters Patent of the United States:

1. A material locating device for a perforating tool of the plier type combining perforating elements; and a sheet of metal having upturned material locating edge portions, disposed at an angle of substantially 90° and diverging outwardly from a point in the general plane of the jaws rearwardly of the perforating elements.

2. A hand punch of the plier type combining a pair of jaw members; a pair of die elements carried by said jaw members; means to effect relative movement of said die elements; and a plate member carried by one of said jaw members and provided with abutments diverging outwardly from a point lying substantially in the plane of the major axis of the jaw members and rearwardly of the die elements and adapted definitely to locate the article to be punched with respect to the die elements.

3. A sheet perforating tool of the plier type combining a pair of handles; a pintle connecting said handles; jaw members actuated by said handles; complementary die elements carried by said jaw members; angularly disposed sheet locating abutments carried by one of said jaw members, diverging outwardly from a point between said pintle and said die elements and so arranged that

the major axis of the jaws bisects the angle between the abutments; and means to detachably secure said abutments to one of said jaw members.

5 4. The combination comprising a punch having the usual relatively movable jaws; complementary male and female die elements carried by said jaws; angularly disposed sheet locating abutments carried by one of said jaws; said abutments converging to a point rearwardly of said female die element and so arranged that the general plane of the jaws bisects the angle formed by said abutments.

10 5. A hand punch for sheet material combining opposed relatively movable jaw members; a complementary means for perforating sheet material inserted therebetween; and means associated with one of said members for accurately locating an angular portion of the sheet material with respect to said perforating means comprising abutment means projecting transversely from a point in the general plane of the jaws and adapted to extend a substantial distance along each edge 15 of the inserted portion of the sheet; and a guard member cooperable with one of said jaw members to form a slotted opening for guiding the sheet into engagement with the abutment means.

20 6. A locating device adapted to be secured to a hand punch of the plier type comprising a sheet of bendable material having upturned edge portions angularly disposed, said edge portions radiating from a common center 25 located rearwardly of the punch elements on a line coincident with the general plane of the jaws, and means for rigidly attaching said sheet to one of the jaws of a hand punch in a predetermined position.

30 40 In witness whereof, I have hereunto subscribed my name.

HAROLD F. SCRIBNER.
